ATTYS

UNITED STATES PATENT OFFICE.

WILLIAM W. BARTLETT, OF SALT LAKE CITY, UTAH TERRITORY.

BED-SPRING.

SPECIFICATION forming part of Letters Patent No. 329,121, dated October 27, 1885.

Application filed October 4, 1884. Serial No. 144,741. (No model.)

To all whom it may concern:

Be it known that I, WILLIAM W. BARTLETT, a citizen of the United States, residing at Salt Lake City, in the county of Salt Lake, Territory of Utah, have invented certain new and useful Improvements in Bed-Springs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has relation to spring-beds of the class known as "slats and springs," and it consists, essentially, in the novel formation of the bail by which the slat is held to the spring, whereby the said bail is prevented from tearing the bed-ticking and efficiently serves for the convenient attachment of the connecting-links.

In the drawings, Figure 1 is a plan view of a bed provided with my improvements. Fig. 2 is an end view of a section thereof. Fig. 3 is a detached perspective view of the upper end of the spring and the fastening-bail. Fig. 4 is a side view of said parts, representing the manner of adjusting the bail in position.

The bed framing, slats, &c., (shown in Figs. 1 and 2), are of ordinary construction, and require no specific description. The springs A are of the ordinary coiled variety, and have their upper ends or coil elongated, as shown at A'. This coil A' is made of a length slightly greater than the width of the slats, so they can project for a slight distance beyond the opposite sides thereof. The fastening-bail B is fitted to extend over the slats, and has its arm B' bent vertically downward, and provided with an eye, b. This eye b is made of an external diameter about equal to the width of space between the sides of coil A', and it rests close under said coil when applied to the slat.

The opposite arm, B², of the bail is bent vertically downward to a point below the coil A', and is then bent laterally outward, and has the eye b' formed on the extremity of its lateral projection.

In applying the bail to the slat, the arm B² has its lateral projection inserted through one end of the coil A' and in the position shown

in full line, Fig. 4. It is then adjusted into the dotted-line position shown in said figure, extended over the slat, and having its arm B' inserted through the end of the coil opposite that engaged by the coil B². In so doing the arms B' B² need be bent slightly toward each other until the arm B' has been adjusted with its eye b below the coil A', when the tension of said arms B' B² will force them upward, so that the eye b on arm B' will project under the bend in the end of coil A', and will be thereby prevented from detachment, as will be understood most clearly from Fig. 3. Thus it will be seen my bail will be easily applied to secure the slats to the springs. The eyes b b' form convenient enlargements to hold the bail from detachment, and also protect the ends of said bail, so they will not tear or otherwise damage the bed-clothing. The links C are connected with and extend between the eyes of the adjacent springs, and so connect the several coil springs, as will be understood from Fig. 1. Heretofore the slats have been secured to the springs by means of bails extended over the slats, and having their ends bent down through the top coil of the spring, and then bent outward in opposite directions, and the springs have been connected by links secured directly to their upper coils. In the former arrangement the ends of the bails have in practice been found to tear the ticking to a considerable degree, and are therefore objectionable. The application of these bails also required the bending of said ends after the said ends were inserted through the coil of the spring. It will be seen that my invention obviates both these difficulties. It provides a bail which will not tear or otherwise damage the bed-ticking, and at the same time furnishes a bail which requires no manipulation or bending after it is applied to the bed. It will also be noticed that the links, when connected directly to the coils of the springs, prevent the tight fitting of the slats to the springs, and leave the same sufficiently loose to permit slight frictional contact or movement, which produces the creaking so objectionable in ordinary spring-beds.

By means of the eyes on my bail the links may be conveniently applied and the slats and springs be tightly joined, as will be understood from Figs. 1 and 2.

Having thus described my invention, what I

claim, and desire to secure by Letters Patent, is—

1. The securing-bail for bed-springs, substantially as herein described, consisting of a metallic rod having its ends bent at approximately a right angle and provided at their extremities with eyes or loops, substantially as set forth.

2. In a spring-bed, the combination of the slat, the spring having its upper coil elongated and extended beyond the sides of the slats, and the securing-bail extended over the slat, and having one arm projected downward through the top coil of the spring, and provided with

the eye *b*, and its other arm extended down 15 through the opposite end of the coil and bent laterally outward thereunder, and provided on its extremity with an eye, *b'*, and the connecting-links looped in said eyes *b b'*, all substantially as and for the purposes specified. 20

In testimony whereof I affix my signature in presence of two witnesses.

WILLIAM W. BARTLETT.
